BLADE DISPENSER

Zemach Auerbach, Bronx, N. Y.

Application June 30, 1949, Serial No. 102,283

12 Claims. (Cl. 30—40)

1 This invention relates to blade dispensers for discharging single blades directly into place in safety razors, and, more particularly, to that type of dispenser in which the lowermost blade of a stack held within the dispenser is discharged to fall flatwise from the bottom of the open bottom of the dispenser.

The invention has particular reference to my prior application, Serial Number 62,260, filed November 27, 1948, and particularly to the first form thereof shown in Figs. 1 to 11 of the earlier application.

In the said first form of the earlier application, the dispenser comprises three parts, viz., the open-bottom container, a slider, and a separate spring element. One of the main objects of the instant invention is to eliminate the need of the separate spring element. An allied object is to provide a blade dispenser of the type described which comprises but two parts, viz., the container proper and the slider. Another allied object is to combine the spring function (of the said third element of the earlier form) with the slider (as will be more fully described herein).

Another object of the instant invention is to provide a blade dispenser of the character described, in which the aforesaid slider is maintained more positively in sliding relationship to the container. A further allied object is to provide the blade dispenser with a slider which is more readily manipulated, and a blade dispenser which will, in general, be better adapted for delivery of single blades.

The blade dispenser of the class described, including the improved dispenser of the instant invention, is designed for use with safety razors having a longitudinal ridge centrally disposed along the top of the blade seat or plate of the razor. Another object of the instant invention is to provide a blade dispenser as described which has special provision for accommodating the said central ridge of the razor.

For the attainment of the foregoing and such other objects of invention as may appear or be pointed out herein, I have shown preferred embodiments of my invention on the accompanying drawing, wherein:

Fig. 1 is a top view, in perspective, of a form of safety razor, with the improved blade dispenser in operative position relative thereto;

Fig. 2 is a top view of the improved dispenser, on a scale larger than that of Fig. 1;

Fig. 3 is a view of the obverse and reverse sides of a single razor blade used in the improved dispenser;

2 Fig. 4 is a longitudinal section taken on the line 4—4 of Fig. 2;

Fig. 5 is a transverse section taken on the line 5—5 of said Fig. 2; and

5 Fig. 6 is a perspective view of a modified form of the improved blade dispenser.

As mentioned in the foregoing statement of invention, the improved blade dispenser comprises but two parts, viz., a container (which is generally designated 11) and a slider (which is generally designated 26).

The container 11 is a shallow open housing rectangular in shape having a top plate 12 and end walls 12a and side wall 12b. The distance 15 between walls 12b is greater than the width of the conventional double-edged blade. The top plate has a centrally-disposed square opening 15 and a pair of substantially similar square openings 14, 14 one on each side of central opening 15, all three openings 14, 15 and 14 being disposed on a longitudinal line centrally through the top plate 12 (and container 11). Also disposed on this longitudinal line and connecting central opening 15 with the end openings on a 20 pair of narrower passages or slots 16, 16.

The slider 26 is formed from a single piece of flat plate stock and is comprised largely of a top arched plate 29; the arched formation of top slide plate 29 is best seen in Fig. 4, from which it will be seen that the central point A of the plate 29 (or slider 26) is the crown point thereof, being furthest removed from the top plate 12 of the container, with both ends, B, B of slider plate 29 in contact with said top plate 12.

35 At the aforesaid central point A of arched slider plate 29, one on each side, are a pair of depending legs 24, 24, which clear through the aforesaid central opening 15. This pair of depending slider legs 24, 24 also clear through a central opening 40 in the blades (subsequently described in detail) contained within container 11. At their lower or distal ends, and at a point underlying the lowermost blade (28, Fig. 4) of the stack within the container, said legs have outwardly-turned feet 25, 25.

The razor blades used in the improved dispenser are of conventional type (designated 20 in the figures) except that they have a central square opening 22, Fig. 3. Square opening 22 is symmetrical upon the central longitudinal axis of the blades. The remote parallel edges of opening 22 are stepped to provide minor steps 21, 21 (nearest the said longitudinal blade axis) and major steps 23, 23 (furthest from said axis). In 50 the blade (20) shown at the top of the sheet,

Fig. 3, the major steps 23, 23 are to the left of the minor steps 21, 21. If the same blade is turned over, so that the reverse side now becomes the obverse side, the major steps 23, 23 are now to the right of the minor steps 21, 21, as in the lower blade 20*, same Fig. 3.

The blades are arranged alternately in the stack formation, with the major steps 23, 23 alternately at the left and alternately at the right. The distance between opposed minor steps 21, 21 of the blade is substantially equal to the transverse width of central opening 15 of top plate 12 of the container, so that the slider legs 24, 24 slide in contact with said minor steps 21, 21. It will be apparent that when the legs 24, 24 are opposite the minor steps 21, 21 of the lowermost blade 28, Fig. 5, the stack of blades (including the lowermost one 28) will be held securely in the container, by reason of the aforesaid feet 25, 25 of the slider legs. The length of these feet 25, 25 (Fig. 5) is somewhat less than the difference or step between the minor and major steps 21, 23 (Fig. 3). Hence when the slider 26 is moved so that legs 24, 24 are now opposite the major steps 23, 23 of the lowermost blade 28 (but at the same time opposite the minor steps of the blade next above it), the lowermost blade will drop out, but the remainder of the stack will be held securely (by reason of feet 25, 25 supporting the minor steps of the aforesaid "next above blade," which is now the lowermost). The stack of blades cannot shift longitudinally nor laterally since the length of the stack of blades is slightly less than the distance between the inside of end walls 12a.

The longitudinal dimension of central blade opening 22 is substantially that of the aforesaid central opening 15 of the container 12. Said central opening 15 serves a further function in providing limit stops defining the left-and-right movement of the slider.

One of the functions of the aforesaid pair of end openings 14, 14 in container plate 12 is to provide guideways for the slider 26. For this purpose, all four corners of the slider plate 29 are recessed, as indicated at 27 in Figs. 1 and 2 (also Fig. 6). It will be noted that the transverse width of arched slider plate 29 is slightly greater than that of the end openings 14, 14, but that the central portion provided in the end edges of plate 29, by the said corner recesses 27, fits snugly within said end openings, 14, 14, of the container.

The slider 26 is fabricated from springy material, such as spring brass or the like. One of the reasons for imparting the aforementioned arched formation to slider 26 is to utilize the springiness of the metal from which fabricated for retaining the slider and the stack of blades securely within the housing (as shown in Fig. 5). Another reason for imparting the arched formation to the slider is to provide sufficient raised surface or protuberance to permit the slider to be readily moved by the fingers.

Except for the already described central opening 22, the blade 20, Fig. 3 is conventional and has the usual cut-outs, including the central longitudinal slot 19, Fig. 3, in which is received the central raised ridge (designated 9 in Fig. 1) of the conventional safety razor. The safety razor (1) shown in Fig. 1 is of the type which, by a twist of a portion of its handle, two side plates (2, 2) swing open to expose the blade platform 3 and the aforesaid central ridge (9) uprising therefrom.

The improved blade dispenser is positioned, in

inverted condition, relative to said blade platform 3 of the "opened" safety razor. By moving slider 26 to the opposite end, from that in which it happens to be, the lowermost blade 28 will drop in proper position, upon blade platform 3.

As pointed out in the statement of invention, the improved blade dispenser has provision for receiving the said longitudinal razor ridge 9. This is one of the reasons for the aforesaid restricted passages or slots 16, 16 connecting the three square openings 14, 15 and 14 of the containing plate 12.

Additionally, the end edges B, B, of the slider are provided with central disposed slots 39, 39, which are sufficiently wide to receive the longitudinal razor ridge 9, so that, at least, the end portions of razor ridge 9 will clear therein.

The top plate 12 of container 11 may have a pair of upstanding arched flanges 17, 17 extending longitudinally one on each side of slider 26 to improve the appearance by concealing the open spaces underlying the arched slider 26. Flanges 17, 17 aid in protecting the slider 26 against accidental displacement or movement.

I claim:

1. A housing for razor blades, said blades having stepped openings, said blades stacked within said housing alternately in reverse position, said housing having a top with an opening, resilient means overlying said top, said resilient means having means for holding a stack of blades within said housing against said top, said blade holding means passing through said top opening in said housing and said stepped openings in said blades to hold the lowermost blade within said housing whereby by moving said resilient means horizontally right and left said blades will be released singly.

2. A housing for razor blades, said blades having a central longitudinal opening, said housing having a top with a central opening, in combination; and a resilient arched slider overlying said top, said slider having a pair of depending legs passing through said opening in said top and said blades, said legs having outwardly turned feet in underlying abutment with the lowermost blade, said top opening providing stops cooperating with said legs to limit the movement of said slider.

3. For use in feeding to a safety razor single blades provided with a central opening, a blade dispenser, in combination, an open container, said container having a top plate, opposed ends and sides, the distance between said sides being greater than the width of said blades, the distance between said ends being slightly greater than the length of said blades, the top plate of the container having a central opening and a slider in overlying relation to said container top plate, said slider having a pair of depending legs clearing through said central container opening and said central blade openings, said pair of legs having outwardly turned feet in underlying abutment with the lowermost blade, said central container opening providing stops cooperative with said slider legs to limit slider movement, said slider being fabricated of springy material and arched to impose a spring condition between abutment of said slider feet with the lowermost blade and abutment of the ends of the arched slider with the said container top plate, the said arched slider presenting a symmetrically elevated surface for facile manipulation.

4. The blade dispenser according to claim 3 wherein said container top plate has a pair of up-

75

standing lips on both sides of said arched slider, to conceal the open space therebeneath.

5. For use in feeding to a safety razor, single blades provided with a central opening, a blade dispenser, in combination, an open container, said container having a plate, opposed ends and sides, the distance between said sides being greater than the width of said blades, the distance between said ends being slightly greater than the length of said blades, the plate of the container having a central opening and a slider in overlying relation to said container plate, said slider having a pair of depending legs clearing through said central container opening and said central blade openings, said pair of legs having outwardly-turned feet in underlying abutment with the lowermost blade, said slider being fabricated of springy material and arched to impose a spring condition between abutment of said slider feet with the lowermost blade and abutment of the ends of the arched slider with the said container plate, the said arched slider presenting a symmetrically elevated surface for facile manipulation.

6. For use in feeding to a safety razor, single blades provided with a central opening, a blade dispenser, in combination, an open container, said container having a plate, opposed ends and sides, the distance between said sides being greater than the width of said blades, the distance between said ends being slightly greater than the length of said blades, the plate of the container having a central opening and a slider in overlying relation to said container plate, said slider having a pair of depending legs clearing through said central container opening and said central blade openings, said pair of legs having outwardly-turned feet in underlying abutment with the lowermost blade, said slider being fabricated of springy material and arched to impose a spring condition between abutment of said slider feet with the lowermost blade and abutment of the ends of the arched slider with the said container plate.

7. For use in feeding to a safety razor having a central longitudinal ridge, single blades of the type having a central longitudinal slot for receiving said razor ridge and provided with a central opening, a blade dispenser, in combination, an open container, said container having a plate, opposed ends and sides, the distance between said sides being greater than the width of said blades, the distance between said ends being slightly greater than the length of said blades, the plate of the container having a central opening and reduced slots of sufficient width to receive the said razor ridge; and a slider in overlying relation to said container plate, said slider having a pair of depending legs clearing through said central container opening and said central blade openings, said pair of legs having outwardly-turned feet in underlying abutment with the lowermost blade, said central container opening providing stops cooperative with said slider legs to limit slider movement, said slider being fabricated of springy material and arched to impose a spring condition between abutment of said slider feet and the lowermost blade and abutment of the ends of the arched slider and the said container plate, the said arched slider presenting a symmetrically elevated surface for facile manipulation, the end portions of said arched slider plate having centrally disposed notches in which said razor ridge is received.

8. For use in feeding to a safety razor single

blades provided with a central opening, a blade dispenser, in combination, an open container, said container having a top plate, opposed ends and sides, the distance between said sides being greater than the width of said blades, the distance between said ends being slightly greater than the length of said blades, the top plate of the container having a central opening and a pair of end openings, and a slider in overlying relation to said container top plate, said slider having a pair of depending legs clearing through said central container opening and said central blade openings, said pair of legs having outwardly-turned feet in underlying abutment with the lowermost blade, said central container opening providing stops cooperative with said slider legs to limit slider movement, said slider being fabricated of springy material and arched to impose a spring condition between abutment of said slider feet and the lowermost blade and abutment of the ends of the arched slider and the said container top plate, the said arched slider presenting a symmetrically elevated surface for facile manipulation, the width of said arched slider being wider than the width of said end container openings, the corners of the arched plate edges being recessed to provide central portions of said slider edges snugly fitted in said end openings for slider guidance.

9. For use in feeding to a safety razor having a central longitudinal ridge, single blades of the type having a central longitudinal slot for receiving said razor ridge and provided with a central opening, a blade dispenser, in combination, an open container, said container having a plate, opposed ends and sides, the distance between said sides being greater than the width of said blades, the distance between said ends being slightly greater than the length of said blades, the plate of the container having a central opening and reduced slots of sufficient width to receive the said razor ridge; and a slider in overlying relation to said container plate, said slider having a pair of depending legs clearing through said central container opening and said central blade openings, said pair of legs having outwardly-turned feet in underlying abutment with the lowermost blade, said central container opening providing stops cooperative with said slider legs to limit slider movement, said slider being fabricated of springy material and arched to impose a spring condition between abutment of said slider feet and the lowermost blade and abutment of the ends of the arched slider and the said container plate, the said arched slider presenting a symmetrically elevated surface for facile manipulation.

10. For use in feeding to a safety razor having a central longitudinal ridge, single blades of the type having a central longitudinal slot for receiving said razor ridge and provided with a central opening, a blade dispenser, in combination, an open container, said container having a plate, opposed ends and sides, the distance between said sides being greater than the width of said blades, the distance between said ends being slightly greater than the length of said blades, the plate of the container having a central opening and a pair of end openings and a pair of reduced slots connecting said central and end openings, the width of said slots being sufficient to receive the said razor ridge; and a slider in overlying relation to said container plate, said slider having a pair of depending legs clearing through said central container opening and said central blade

openings, said pair of legs having outwardly-turned feet in underlying abutment with the lowermost blade, said central container opening providing stops cooperative with said slider legs to limit slider movement, said slider being fabricated of springy material and arched to impose a spring condition between abutment of said slider feet and the lowermost blade and abutment of the ends of the arched slider and the said container plate, the said arched slider presenting a symmetrically elevated surface for facile manipulation, the ends of said arched slider plate cooperating with said end container openings for slider guidance.

11. For use in feeding to a safety razor having a central longitudinal ridge, single blades of the type having a central longitudinal slot for receiving said razor ridge and provided with a central opening, a blade dispenser, in combination, an open container, said container having a plate, opposed ends and sides, the distance between said sides being greater than the width of said blades, the distance between said ends being slightly greater than the length of said blades, the plate of the container having a central opening and a pair of end openings and a pair of reduced slots connecting said central and end openings, the width of said slots being sufficient to receive the said razor ridge; and a slider in overlying relation to said container plate, said slider having a pair of depending legs clearing through said central container opening and said central blade openings, said pair of legs having outwardly-turned feet in underlying abutment with the lowermost blade, said central container opening providing stops cooperative with said slider legs to limit slider movement, said slider being fabricated of springy material and arched to impose a spring condition between abutment of said slider feet and the lowermost blade and abutment of the ends of the arched slider and the said container plate, the said arched slider presenting a symmetrically elevated surface for

facile manipulation, the width of said arched slider being wider than the width of said end container openings, the corners of the arched plate edges being recessed to provide central portions of said slider edges snugly fitted in said end container plates, for slider guidance.

12. For use in feeding to a safety razor, single blades provided with at least one opening, a blade dispenser, in combination, an open container, 10 said container having a plate, opposed ends and sides, the distance between said sides being greater than the width of said blades, the distance between said ends being slightly greater than the length of said blades, the plate of the container having at least one opening substantially corresponding to said blade opening, and a slider in overlying relation to said container plate, said slider having a pair of depending legs clearing through said container opening and said blade opening, said pair of legs having outwardly turned feet in underlying abutment with the lowermost blade, said slider being fabricated of springy material and arched to impose a spring condition between abutment of said slider feet 20 with the lowermost blade and abutment of the ends of the arched slider with the said container plate.
